UNITED STATES PATENT OFFICE.

THEODOR E. HOENEMANN, OF BOSTON, MASSACHUSETTS, ASSIGNOR TO THERMO-WALL CONSTRUCTION COMPANY, OF BOSTON, MASSACHUSETTS, A CORPORATION OF MASSACHUSETTS.

BUILDING CONSTRUCTION.

Application filed May 5, 1921. Serial No. 466,979.

To all whom it may concern:

Be it known that I, THEODOR E. HOENEMANN, a citizen of the United States, residing at Boston, in the county of Suffolk and State of Massachusetts, have invented a new and useful Improvement in Building Constructions, of which the following is a specification, reference being had therein to the accompanying drawings.

My invention relates to building construction and more particularly to a hollow wall form of construction made up entirely of concrete blocks.

The use of concrete for building purposes has been restricted and limited because of the fact that moisture readily penetrates and passes through concrete, whether in mass or block form. Although this disadvantage may be obviated by the construction of hollow walls having no direct continuous concrete bond between the inner and outer surfaces for the passage of moisture, yet, heretofore, the cost of such form of construction has been prohibitive. In spite of the cheapness of concrete as a material, it has not as yet gone into general use for buildings other than factories because of the foregoing conditions.

The main object of my invention is the provision of a concrete block construction capable of being used for any type of building and for any purpose, which is absolutely damp-proof and to this end the walls are so constructed that there is no direct bond between the outer and inner surfaces of the walls for the passage of moisture or dampness.

Another object of the invention is the provision of a form of construction which is simple, which can be built rapidly and with a minimum of labor, and which is cheap.

Other objects of the invention will be more specifically set forth and described hereinafter.

My invention contemplates broadly a building construction made up of concrete blocks so laid and arranged that the walls are provided with an interior continuous air space to interrupt and prevent the passage of moisture from the outer face of the wall to its inner face. In its simplest form, my invention contemplates a wall made up of two walls separated by an air space, but bonded together by transverse blocks. Each wall is preferably composed of a series of

courses of concrete blocks, the joints in each course being staggered in relation both to the joints in the adjoining courses in the same wall and to the joints in the corresponding course in the other wall. Each wall is provided with inwardly projecting transverse blocks which are arranged at suitable intervals between the longitudinal blocks which for the most part make up the two walls, but in no case does any transverse block extend from one wall to the other. For securing the bond the transverse blocks are arranged in vertical series and project alternately from the two walls so that each transverse block in either wall is cemented to and between a transverse block above and one below incorporated in the other wall.

In the accompanying drawings, Figure 1 is an isometric view of a corner portion of a double wall constructed in accordance with my invention and showing the preferred and simplest embodiment thereof; Fig. 2 is an isometric view of a corner portion of a triple wall showing the application of my invention to a construction heavier than that illustrated in Figure 1; Fig. 3 is a similar view of a quadruple wall illustrating a further development and application of the invention; and Fig. 4 is an isometric view of a double wall construction showing a column constructed at the intersection of three walls.

Referring to the drawings, Figure 1 shows a structure, embodying the simplest form of the invention, which is made up of two single walls bonded together into a double wall having an interior air space. Each single wall is built up of comparatively thin rectangular concrete blocks 10 set on their longitudinal edges and laid in courses with the joints of each course staggered with relation to the joints of the next adjacent course both below and above it. At the same time the joints in the courses in each wall are staggered with relation to the joints in the respective courses in the other wall. The two single walls are separated from each other by an air space and the width of this air space may be varied within certain limits to suit varying conditions.

In order to unite the two walls into a unitary structure, transverse blocks 12 are provided which may be laid in alternate arrangement with the blocks 10 as shown in

Figure 1, or may be laid at greater intervals. Each transverse block 12 is of a length less than the distance from the outside surface of one wall to the inside face of the other wall so that when laid in position in one wall it will not engage the other wall, thereby leaving a narrow air space between the inner end of the block 12 and the inner face of the other wall. Owing to the fact that the joints in each wall are staggered with relation to the joints in the other wall, each transverse block in one wall is supported by a similar block laid in the other wall and in turn itself supports a transverse block laid in the other wall.

For all practical purposes such a construction is substantially moisture proof since it offers no direct bond for the passage of moisture from the outside to the inside of the structure. The only possible route is circuitous, from the outer wall of the structure through a transverse block and then either downwardly or upwardly to another transverse block and thence to the inner wall. Through such a roundabout way no appreciable amount of moisture would ever find its way. However, to avoid any possibility of any dampness reaching the interior, the inner ends of the transverse blocks may be coated with any suitable waterproofing substance, which will offer an effective bar to moisture.

In building this wall the blocks are all held together by mortar or cement 15 to form a unitary structure, the two single walls being built up and bonded together as the work proceeds. Although the blocks may be made of any suitable material and in any way and of any suitable size, yet I prefer to use blocks made of concrete and of the general form shown in the drawings. I also prefer to use blocks made by a machine shown and described in United States Letters Patent No. 1,398,898, issued to me Nov. 29, 1921, since the blocks may be produced rapidly and at a low cost. Furthermore by the use of said machine blocks may be made having some or all surfaces either finished or roughened to receive a stucco coating. By the use of such blocks in any building construction any condition of outer and inner surfaces of the walls may be secured.

In Figure 2 of the drawings, I have shown a further development of my invention in which it is applied to a heavier form of construction, namely, a triple wall comprising three walls joined together into a unitary structure by broken bonds. The addition of a third wall makes possible various combinations or arrangements of the blocks but all, however, involving the same general principle. In Figure 2 are shown two of the arrangements which will illustrate the possibility of other combinations.

65 In the lower wing of that wall, the blocks

10 are laid in the outer and middle walls as shown in Figure 1 and in the inner wall similar to the middle wall. For bonding the three walls together, transverse blocks of three different dimensions are employed. 70 Transverse blocks 12 are incorporated in the outer wall and are supplemented by shorter blocks 14 interposed between the middle and inner walls for forming one broken bond between the three walls. This form of bond alternates in both vertical and horizontal directions with a bond made by a longer transverse block 16 incorporated in the inner wall and passing through the middle wall, nearly to the outer wall. 75 80

In the upper wing of the wall shown in Figure 2, the blocks 10 are arranged in the outer and inner walls as in the lower wing, but the bonds are secured by using blocks 16 only. This necessitates the use of short blocks 18 alone in constructing the middle wall, since each transverse block 16 whether incorporated in the outer or the inner wall, passes through the middle wall.

As illustrating the amplification possible in the use of my invention, there is shown in Figure 3 a quadruple wall. Here, as in Fig. 2, the scope of the construction permits of many combinations of blocks and of breaking the transverse bond at different points and at one or more points in each bond. Preferably, however, I prefer to construct the two outer walls alike and the two inner walls also alike so that the joints of each two walls making up a pair are in alignment and the joints of each pair are in staggered relation to the joints of the other pair. The bonds are then made by long transverse blocks 20 and short blocks 22, the blocks 20 projecting inwardly from first the outer wall and then from the inner wall, as shown in the drawings. In each case the inner end of the transverse block 20 engages a block 10 in one of the inside walls and the bond is broken by means of the short block 22 either at the outer wall or at the inner wall. The bond may be broken also, if desired, at the inner end of each block 20 by slightly reducing the length of those blocks.

In Figure 4 is shown a double wall construction in which a column is provided at the intersection of two walls running perpendicular to each other; illustrating the possibility of using my invention in pier construction. The construction of Figure 1 is shown as applied to the double walls in Figure 4 but not to the pier, since, because of its depth and air spaces, there is little likelihood of moisture reaching the interior of the structure through the pier. The latter may, however, if desired, be constructed with broken joints and the changes necessary to accomplish this result would be, from an inspection of the other figures, apparent to one skilled in the art. 130

It will be observed from the foregoing that my method is capable of innumerable applications and to an unlimited extent since it can be expanded to any thickness and in any or all directions.

My building construction has many advantages. It may be easily and rapidly constructed because the various blocks of which it is built up are sufficiently light in weight to be handled by one workman and thereby can be placed in the wall with full mortar joints. This is an important consideration because imperfect joints are productive of deleterious consequences, since they permit water to go through and the walls to crack and to settle, besides undermining and reducing the strength of the wall. The wall may be built with both the inside and the outside faces straight and true. Blocks having finished surfaces may be used for the outside face of the wall which will require no further treatment, or blocks having roughened surfaces may be employed in order to receive an outside stucco finish. Because of the fact that moisture or dampness cannot penetrate through the wall, plastering may be applied directly to the inside face of the wall without requiring the use of furring.

It is to be understood that my invention is not to be limited to the various embodiments herein shown and described but may be exemplified by various other constructions all within the purview of the invention and the scope of the following claims.

What I claim is:—

1. A building construction comprising two walls each made up of a plurality of courses of blocks arranged alternately, longitudinally and transversely the wall, the transverse blocks of each course being staggered in relation to the transverse blocks of the adjacent courses and the blocks in each course in one wall being staggered in relation to the blocks in the corresponding course in the other wall, each of said transverse blocks extending inwardly from the wall in which it is set partially toward the inner surface of the other wall and being in each case opposite the center of a longitudinal block in said other wall and leaving an air space between the inner end of the transverse block and the opposite wall.

2. A building construction comprising a double wall, each wall comprising a plurality of courses made up of blocks arranged alternately in a longitudinal and transverse relation to the wall, the respective courses in the two walls being at the same level with each other and the transverse blocks in each wall extending partially only toward the other wall in order to leave an air space between the inner end of each transverse block and the other wall.

3. In a building construction, the com-

bination of two walls composed of a plurality of courses of alternate longitudinal and transverse blocks, the blocks in each course being staggered in relation to the blocks in the adjoining courses and each of said transverse blocks in each wall extending only partially toward the other wall in order to leave an air space between its inner end and the other wall.

4. In a building construction, the combination of a plurality of parallel walls with air spaces between, each wall being made up of a plurality of courses composed of blocks arranged alternately in a longitudinal and transverse relation to the wall; said transverse blocks serving to bond said walls together into a unitary structure but each transverse block extending only partially toward the adjacent wall in order to leave an air space between its inner end and said adjacent wall.

5. A building construction comprising two walls with an air space between, each wall being made up of blocks laid in horizontal courses and said two walls being bonded together at intervals by vertical rows of transverse blocks, the said transverse blocks in each row projecting alternately first from one wall and then from the other wall and each block incorporated in one wall extending partially only toward the other wall and being held in place between two blocks projecting from the other wall; each of said transverse blocks in each wall being centrally disposed in relation to the longitudinal blocks in the adjacent courses in the same wall in the corresponding courses in the other wall.

6. A building construction comprising a plurality of walls with air spaces between the adjacent walls, each wall being made up of blocks laid in horizontal courses and said walls being bonded together by vertical rows of transverse blocks at suitable intervals, each transverse block being incorporated in one wall and extending partially only toward the adjacent wall and being held in place between two similar transverse blocks projecting from the adjacent wall; each of said transverse blocks in each wall being centrally disposed in relation to the longitudinal blocks in the adjacent courses in the same wall in the corresponding courses in the other wall.

7. In a building construction, the combination of two parallel but separated walls, each composed of a plurality of courses of alternate longitudinal and transverse blocks, the blocks in each course being centrally staggered in relation to the blocks in the adjoining courses and each of said transverse blocks in each wall extending only partially toward the other wall and having its inner end coated with a water-proofing material.

8. In a building construction, the combination of two parallel but separated walls, each composed of a plurality of courses of alternate longitudinal and transverse blocks, 5 the blocks in each course being centrally staggered in relation to the blocks in the opposite and adjoining courses and each of said transverse blocks in each wall extending partially only toward the other wall in 10 order to leave an air space between its inner end and the other wall and having said inner end coated with water-proofing material.
9. In a building construction, the combination of a plurality of parallel walls with air spaces between, each wall being made up of a plurality of courses composed of blocks arranged alternately in a longitudinal and transverse relation to the wall; each of said 15 transverse blocks extending partially only toward the adjacent wall in order to leave an air space between its inner end and the said adjacent wall and having said inner end coated with water-proofing material.
10. In a building construction, the combination of a plurality of walls, each wall made up of a plurality of courses of blocks set on their longitudinal edges alternately longitudinally and transversely the wall, the transverse blocks in each course being 20 staggered in relation to the transverse blocks in the adjacent courses in the same wall and the opposite course in the other wall, and the blocks in each course in each wall being staggered in relation to the block in the 25 corresponding course in the other wall and each of said transverse blocks extending inwardly from the wall in which it is set partially toward the inner surface of the other wall and opposite the vertical center line of a longitudinal block in the corresponding course in said other wall, leaving an air space between the inner end of the transverse block and said longitudinal block.

In witness whereof, I hereunto set my hand this twenty-first day of April, 1921.

THEODOR E. HOENEMANN.
